AUTOMATICALLY GOVERNED PUMP

Clarence J. Coberly, Los Angeles, Calif., assignor
to Roko Corporation, Reno, Nev., a corporation
of Nevada

Application May 18, 1938, Serial No. 298,593

16 Claims.

(CL 103—46)

This invention relates to the pumping art, and more particularly to fluid operated pumping equipment.

The invention is of particular utility in the oil industry and, consequently, is described in connection with such use, although it is to be understood that I do not intend to be limited thereby, since the invention is susceptible of other diverse uses.

This invention is an improvement over the devices disclosed in my copending patents, No. 2,119,736, issued June 7, 1938, for Governed fluid operated pump, and No. 2,119,737, issued June 7, 1938, for System of operating fluid-operated pumps.

Fluid operated pumps for use in deep wells ordinarily include a fluid motor with a pump unit operatively connected thereto adapted to pump oil, or other well fluid, from the well up through a production tubing leading to the top of the well. For actuating the fluid motor, operating fluid such as oil is pumped under relatively high pressure from the top of the well downwardly through a supply tubing which connects to the fluid motor. As long as the device is pumping oil from the well formation, it will operate at a normal speed, but it frequently occurs that gas forms in or enters the pump so that, instead of a liquid being pumped, the pumping mechanism is operating against a compressible gas, the result being that a material portion of the pumping load is removed and the pumping mechanism then races or operates at high speed until the gas is removed from the pumping unit.

Such fluid operated pumps are ordinarily operated at relatively great depths in oil wells, and, accordingly, a large volume of operating fluid under high pressure is confined in the supply tubing between the pumping mechanism and the operating pump on the surface of the ground which supplies the operating fluid. Due to the compressibility of this large volume of operating fluid, a large amount of energy is stored in it under these conditions of operation. If for any reason the pumping load on the fluid operated pump decreases, due to the presence of gas in the well fluid, failure of the pump valve to seat properly, or due to any other cause, the operating fluid in the supply tubing expands as a result of the release of the energy of compression stored therein, causing the pump to run at excessive speeds until the load is again raised by removing the gas from the pump or otherwise rectifying the condition. The pump may thus race for a portion of a

stroke or for a number of successive strokes, and in any event the pump will operate at excessive speed until all of energy of compression stored in the operating fluid is released, or until the pumping load is again applied to the pump.

When a fluid operated pump runs at excessive speed, it may be very harmful to certain parts of the pumping equipment. This is particularly true when the pump cylinder is only partially filled with well fluid, in which case the pump piston will move at extremely high speed during the first part of its stroke while it is compressing the gas therein and will then strike the liquid therein while moving at high velocity. This introduces a hydraulic shock load which results in excessive stresses on the parts of the pump and may cause considerable damage in the form of excessive wear or breakage of the parts. Evidence has also been found which indicates that a pressure wave may be set up in the column of operating fluid in the supply tubing which causes cavitation in the column directly above the pumping mechanism. Together with this condition of cavitation in the operating fluid, there may also be an excess pressure in the column of discharge fluid in the production tubing, and in any event if there is a difference in pressure in the direction reverse to that of normal operation, discharge fluid from the production tubing may be caused to back up through the fluid motor valve into the fluid motor cylinder. Since the discharge fluid frequently contains water, sand, or other undesirable foreign materials harmful to the working parts of the fluid operated pump, this condition will be extremely harmful to the working parts in addition to the undesirable stresses which it may introduce. Ordinarily in operating a fluid operated pump, considerable care is taken to obtain clean operating fluid by the use of filtering equipment and otherwise, and the purpose thereof is defeated if water, sand, or other undesirable foreign materials are allowed to back up into the working parts of the fluid motor.

To prevent such a fluid operated pump from racing at excessive speeds under the conditions discussed, a governor mechanism may be provided in the supply tubing conveying operating fluid to the pump immediately thereabove which will control the rate of flow of operating fluid to the fluid motor and prevent it from exceeding a safe limit of speed. My above noted Patents No. 2,119,736 and No. 2,119,737 show such governors providing means for controlling the rate of flow of operating fluid, which governors may be adjusted before they are run into the well, and also

show means of adjusting the flow control thereof after the governors have been run into the well by movement of the operating fluid supply tubing. It is very inconvenient to remove such governors from the well for the purpose of adjustment of the flow control setting mechanism thereof, and it is frequently inconvenient or impossible to adjust a governor in a well satisfactorily by moving the supply tubing to attempt to meet well flow conditions which may constantly vary.

It is therefore a primary object of my invention to provide a fluid operated pumping device for deep wells having incorporated therewith means for preventing the above discussed undesirable conditions.

It is a further object of my invention to provide a fluid operated pumping device for deep wells in combination with a flow governing device for controlling the flow of operating fluid to the pumping device in response to changes in the rate of flow of operating fluid thereto.

Another object of the invention is to provide a flow governing device which will automatically adjust its flow capacity in response to changes in the rate at which operating fluid is supplied thereto.

Still another object of the invention is to provide a fluid operated pumping device for deep wells having incorporated therewith a fluid flow governor set in the well including means for changing the normal flow capacity of the governor from the surface of the ground without withdrawing the same from the well or moving any of the tubing in the well.

A further object of the invention is to provide a fluid flow governor for controlling a flow of fluid therethrough, the fluid flow capacity thereof being variable in response to a very gradual change in the rate of flow therethrough. To accomplish this, I prefer to provide a governor requiring a certain definite time interval to adjust itself to the increased or decreased rate of fluid flow therethrough.

A still further object of my invention is to provide a fluid flow governor having a main valve for controlling the flow of fluid through the governor, a metering orifice in series with the main valve through which the fluid flows to impress a pressure differential on a piston member which controls the operation of the main valve, and an adjustable control means for controlling the operation of the piston member.

A further object of my invention is to provide a flow governor adapted to maintain the rate of flow of fluid therethrough below a predetermined maximum irrespective of momentary changes in the rate of flow, but responsive to a continued change in the rate of flow to readjust the maximum normal flow capacity thereof.

A further object of my invention is to provide a flow governor adapted to permit a sudden predetermined increase in the rate of flow above the then established or prevailing rate of flow in response to momentary changes in load, but which automatically requires further increase in the rate of flow to be gradual and in response to an increased rate of flow maintained over a sustained period.

Another object of the invention is to provide a fluid flow valve having opposed ports so that any unbalance normally produced by low pressure areas produced by high rates of flow of fluid therethrough will be substantially equal and opposite so as to neutralize the effect thereof.

Still another object of the invention is to pro-

vide a fluid flow valve having ports cooperating with a valve stem, in which fluid pressures on the valve stem are equalized to prevent fluid leakage along the stem tending to clog or jam the valve stem by the introduction of sand or other foreign materials.

Other objects and advantages will appear in the following specification and in the drawings, in which:

10 Fig. 1 is a diagrammatic view, partly in section, of my invention installed in a well.

Fig. 2 is a vertical sectional view of my invention showing the control valve in fully opened position and the main valve in partially closed position.

Fig. 3 is an enlarged sectional view taken on the line 3—3 of Fig. 2.

Fig. 4 is an enlarged sectional view taken on the line 4—4 of Fig. 2.

Fig. 5 is an enlarged sectional view taken on the line 5—5 of Fig. 2.

Fig. 6 is an enlarged sectional view taken on the line 6—6 of Fig. 2.

Fig. 7 is an enlarged sectional view taken on the line 7—7 of Fig. 2.

Fig. 8 is a vertical sectional view of my invention showing the control valve in partly closed position and the main valve in fully opened position.

Fig. 9 is a vertical sectional view of my invention showing the control valve and main valve in fully opened positions.

Referring to Fig. 1 of the drawings, I show a well having a well casing 20 perforated at its lower end as is common in the art to permit well fluid to flow thereto from the well formation, and having a casing head 21 provided at its upper end from which it is suspended. Also suspended from the casing head 21 is a production tubing 22 having secured at its lower end an inlet check valve member 23 provided with an inlet opening 24 communicating with a conical pump seat 25 adapted to receive in seating relation the lower tapered end of a fluid operated pump 26, a ball valve member 27 being provided to seat in the inlet opening 24 to permit well fluid to flow through the inlet check valve member into the fluid operated pump but preventing a reverse flow thereof. The fluid operated pump 26 may be of any suitable type well known in the art, but I prefer to use a fluid operated pump such as shown and described in my above Patent No. 2,119,736, to which reference is hereby made for the details of construction thereof.

Connected to the upper end of the fluid operated pump 26 is an inlet pipe 28 to which is connected the flow governor 30 of my invention. Connected to the upper end of the flow governor 30 is a string of supply tubing 31 which extends through the casing head 21 to a surface pumping mechanism 32 of any suitable type adapted to pump an operating fluid, such as clean oil, under high pressure downwardly through the supply tubing 31, the flow governor 30, and the inlet pipe 28 to the fluid operated pump 26 to actuate the same. Also connected to the casing head 21, and communicating with the production tubing 22, is a discharge pipe 33 adapted to convey fluid discharging therethrough to a point of discharge or use (not shown).

The flow governor 30, as shown in Figs. 2, 8, and 9, has an outer tubular shell 35 which is connected at its lower end through a lower collar 36 to the inlet pipe 28, and is connected at its

upper end through an upper collar 37 to the lower end of the supply tubing 31.

In general, the flow governor 30 is comprised of a valve actuating means 38 for actuating a main valve means 39, and a control valve means 40 for controlling the operation of the valve actuating means 38. The valve actuating means 38 is comprised of a valve piston 41 having a central chamber 42 therein, an upper bore 43, and downwardly extending passages 44 in the lower face of the valve piston, there being an annular space 45 between the bore 46 of the outer tubular shell 35 and the outer surface of a tubular extension 47 formed on the lower face of the valve piston 41. The passages 44 are made as large as possible without weakening the structure. Threaded into the lower end of the tubular extension 47 is a plug element 48 which closes the lower end thereof. The valve piston 41 is adapted to reciprocate in the bore 46 of the outer tubular shell 35 and is provided with suitable piston rings 49 for forming a substantially fluid-tight fit therebetween.

The main valve means 39 is comprised of a tubular valve body 50 spaced from the outer tubular shell 35 to provide an annular space 51 therearound and having a head portion 52 which makes a fluid-tight fit with the walls of the bore 46 of the outer tubular member 35. The lower end of the tubular valve body 50 is closed by a plug member 53 threaded therein which seats on an upper shoulder 54 formed by the upper end of the lower collar 36, and has radial openings 55a communicating between the annular space 51 and the inlet pipe 28 through the lower collar 36. The head portion 52 is provided with an upper valve passage 55 and a lower valve passage 56 which are provided with annular recesses 57 and 58, respectively. The plug member 53 is internally bored at 59 to receive the lower end of a main valve spring 60, the upper end of which engages an annular plate member 61 provided with a counterbore 62 which receives a lower head portion 63 of a main valve piston 64 which extends upwardly through the head portion 52 of the tubular valve body 50 and into a suitable opening formed in the plug element 48 of the valve actuating means 38. Annular recesses 65 and 66 are formed on the main valve piston 64, being separated by a valve head 67.

The tubular valve body 50 is provided with a central bore 68 in the upper end of which is a valve seat member 69 which is pressed into the head portion 52 and which makes a fluid-tight fit with the central bore 68. The valve seat member 69 has an axial bore 70 in which the main valve piston 64 makes a close sliding fit, the upper end of the bore 70 communicating through a radial opening 71 with the annular recess 57, being separated by an annular shoulder 72 from a valve chamber 73 formed therein which communicates through a radial discharge opening 74 and a radial opening 75 formed in the tubular valve body 50 with the annular space 51. The lower end of the valve chamber 73 is partially closed by an annular lower shoulder 76. The main valve piston 64 fits into a recess in the plug element 48 so as to hold it centered, and bears against the bottom of the recess so that the piston moves in response to movement of the valve actuating means 38.

The control valve means 40 includes a control piston 80 making a close sliding fit in a control cylinder 81 formed in the tubular extension 47 of the valve piston 41, and a shoulder 82 formed

10 by the plug element 48 acts as a limiting stop to limit downward movement of the control piston 80 in the control cylinder 81. A helical control groove 83 is formed on the outer surface 5 of the control piston 80 and provides a restricted communication between the upper and lower ends of the control piston. The cross-sectional area, hydraulic radius, and length of the control groove 83 are important, as will be described herein-after. The control piston 80 is provided with a cylindrical chamber 84 in its lower end, and a downwardly projecting tubular stem 85 is threaded into the control piston, the tubular stem having an axial passage 86 communicating between the chamber 84 and a check valve chamber 87 formed in the control piston. As will be noted, the tubular stem 85 projects below the lower end of the control piston 80 and is adapted to engage the plug element 48 to act as a stop means to limit downward movement of the control piston 80. A control spring 88 is provided in the cylindrical chamber 84 in the space between the tubular stem 85 and the control piston 80 and engages the plug element 48 and the control piston 80, the spring being under compression so as to exert an upward force on the control piston tending to maintain it in its uppermost position. Carried in the check valve chamber 87 is a ball valve element 89 adapted to seat in the upper end of the axial passage 86 to prevent a downward flow of fluid therethrough but permitting an upward flow of fluid therethrough. The check valve chamber 87 communicates through a radial orifice 90 formed in the control piston 80 with the control groove 83, and the point of connection thereto is an important feature of the invention, as will be described hereinafter.

40 Formed on or connected to the upper end of the control piston 80 is a cylindrical control element 91 which has a conical bore 92, the control element being provided with upwardly opening V-notches 93, preferably four in number, around the periphery thereof. The control element 91 extends through the upper bore 43 of the valve piston 41, and when it is in its lowermost position, as shown in Fig. 2, the area of the V-notches 93 is at a maximum. When the control element 91 is in its uppermost position, the base portion 94 thereof will completely close the upper bore 43 to prevent any fluid from passing therethrough.

In operation, the elements are installed in the well casing 20 as shown in Fig. 1, and operating fluid under relatively high pressure is conveyed by the surface pumping mechanism 32 through the supply tubing 31, the flow governor 30, and the inlet pipe 28 to the fluid operated pump 26 to operate the same to pump well fluid from the well casing 20 through the inlet check valve member 23, the fluid operated pump 26, and the production tubing 22 to the top of the well from which it is discharged through the discharge pipe 33 to a suitable point of use or storage (not shown).

In passing through the flow governor 30, the operating fluid flows from the supply tubing 31 through the upper collar 37 and into the upper end of the bore 46 of the outer tubular shell 35 above the valve piston 41. It then passes through the V-notches 93 of the control element 91, through the central chamber 42, and discharges through the passages 44 into the annular space 45. It then passes downwardly through the annular space 45 and through the upper and lower valve passages 55 and 56 and the annular

recesses 51 and 58 into the valve seat member 69 through the radial opening 71 and into the central bore 68 below the valve seat member 69. It will be noted that the main valve piston 64 has an upper shoulder 95 thereon formed by the upper end of the annular recess 66, and that the valve head 67 has a lower shoulder 96 formed thereby, and that the upper shoulder 95 is spaced from the annular shoulder 72 the same distance that the lower shoulder 96 is spaced from the annular lower shoulder 76, regardless of the position of the main valve piston 64, and the spacings thereof permit equal flows of operating fluid from the upper and lower valve passages 55 and 56, respectively, into the valve chamber 13 from opposite directions, and any unbalance of the valve piston 64 produced by low pressure areas at high rates of flow of operating fluid will be equal and opposite and therefore will neutralize each other. Thus, my main valve means 39 will be fully balanced at any rate of flow, an attainment not possible with my prior types of flow valves. Furthermore, it will be noted that since the fluid pressures on the main valve piston 64 balance each other, there will be no leakage of operating fluid along the piston tending to force undesirable foreign materials, such as sand, into the sliding fit thereof. These features are an important part of the invention and greatly add to the reliability of the main valve means 39 under operating conditions.

The operating fluid then passes from the valve chamber 13 through the radial discharge opening 74 and the radial opening 75 into the annular space 51, through which it passes downwardly and through the radial openings 55a of the plug member 53 into the lower collar 36, from which it passes through the inlet pipe 28 to the fluid operated pump 26.

The flow governor 30 is adapted to control the rate of flow of the high pressure operating fluid flowing through the supply tubing 31 and inlet pipe 28 to the fluid operated pump 26. The main valve means 39 is adapted to control the rate of flow of operating fluid therethrough in response to movement of the valve actuating means 38, the main valve means 39 permitting a high rate of flow of operating fluid therethrough with a low pressure drop when it is in opened position, as shown in Figs. 8 and 9, in which the valve actuating means 38 is in its uppermost position, and greatly increasing the pressure drop for the same rate of flow when the valve actuating means 38 is in a lower position, as shown in Fig. 2. The V-notches 93 of the control valve means 40 form a metering orifice means 97 which is in series through the passages 44 of the valve actuating means 38 with the main valve means 39.

Operating fluid flowing under high pressure through the metering orifice means 97, the central chamber 42, and the passages 44 creates a pressure differential between the upper and lower faces of the valve piston 41 which tends to depress the valve piston 41, and consequently the main valve piston 64, against the opposing action of the main valve spring 60. The main valve spring 60 is normally adjusted before the flow governor 30 is installed in the well to provide a predetermined upward force urging the main valve piston 64 toward open position and urging the valve piston 41 upwardly. As long as the pressure differential on the valve piston 41 is less than the upward force exerted by the main valve spring 60, the main valve means 39 will remain in its fully open position, as shown in

Figs. 8 and 9. If, however, the pressure differential on the valve piston 41 increases above the force exerted by the main valve spring 60, the valve piston 41 will move downwardly until the pressure differential thereon is balanced by the upward force of the main valve spring 60, carrying with it the main valve piston 64, thus closing or partially closing the main valve means 39, as shown in Fig. 2, to throttle the flow of operating fluid therethrough. The throttling action of the main valve means 39 is substantially proportional to the amount the pressure differential on the valve piston 41 exceeds the predetermined value for which the main valve spring 60 is designed, so that the throttling action of the main valve means 39 will increase as the excess pressure differential on the valve piston 41 increases and will decrease as the excess pressure differential thereon decreases. Undesired changes in pressure differential on the valve piston 41 are ordinarily caused by changes in the rate of flow of operating fluid through the metering orifice means 97, which usually result from a change in load conditions on the fluid operated pump 26. Since the surface pumping mechanism 32 is of the positive displacement type, the change in rate of flow of operating fluid may be due to the expansion of the operating fluid when the load on the fluid operated pump 26 is reduced.

Operation of the control valve means 40 is as follows. The control valve means 40 presents a constant area to the upstream pressure of the operating fluid in the upper collar 31 and central chamber 42 of the valve piston 41, and the control spring 88 exerts a substantially constant upward force on the control piston 80 tending to hold the control piston 80 in its upper or closed position. Operating fluid flows through the V-notches 93 and the central chamber 42 and exerts a downward force on the projected area of the control element 91 of the control piston 80 tending to balance the upward force of the control spring 88, the control piston 80 moving downwardly to a position in which the V-notches 93 which form the metering orifice means 97 provide sufficient area of opening so that the drop in fluid pressure across the metering orifice means 97 multiplied by the projected area of the control element 91 of the control piston 80 exactly balances the upward force exerted by the control spring 88. There will, therefore, be a constant drop in fluid pressure through the metering orifice means 97 and, therefore, a constant fluid pressure differential between the upper and lower faces of the valve piston 41. If the flow of operating fluid is reduced to zero, the upward force exerted by the control spring 88 will cause the control piston 80 to move upwardly to its fully closed position in which the V-notches 93 pass beyond the lower edges of the bore 43 and the base 94 thereof completely closes the bore 43. On the other hand, if the flow of operating fluid is increased, the fluid pressure drop across the metering orifice means 97 is increased and overbalances the upward force exerted by the control spring 88, and the control piston 80 will move downwardly to a position in which the V-notches 93 have a greater area of opening so as to permit the increased flow of operating fluid therethrough. Thus, so long as operating fluid is flowing through the metering orifice means 97, the drop in fluid pressure thereacross will be maintained at a substantially constant predetermined value. The only change in pressure

drop across the metering orifice means 97 will be due to the change in load on the control spring 88 due to the change in deflection thereof. However, the initial deflection of the control spring 88 is preferably ten to twenty times the change in deflection thereof due to the movement of the control piston 80, and, therefore, the fluid pressure drop across the metering orifice means 97 will not vary more than from 5% to 10%.

If the above noted ratio of the force of the control spring 88 to the projected area of the control piston 80 is such that the pressure differential applied to the valve piston 41 is slightly less than the upwardly opposing force of the main valve spring 60, the valve actuating means 38 will remain in its upper position, as shown in Figs. 8 and 9, and the main valve means 39 will remain in its open position. If, for example, the pressure differential between the upper and lower faces of the valve piston 41 is 20% less than the force required to move the main valve piston 64 against the upward force exerted by the main valve spring 60, then the main valve means 39 will remain in open position and the control piston 80 will vary its position in accordance with the rate of flow through the metering orifice means 97.

The rate of movement of the control piston 80 depends upon the rate at which operating fluid will flow through the helical control groove 83 and the force which is applied to the control piston to cause it to move. If the pressure differential across the metering orifice means 97 drops below the upward force exerted by the control spring 88, the control piston 80 will start to move upwardly toward closed position, and operating fluid will flow downwardly through the helical groove 83 to keep the lower end of the control cylinder 81 filled with operating fluid. The strength of the control spring 88 and the cross-sectional area and hydraulic radius and length of the control groove 83 are preferably formed so that the control piston 80 will move its full distance of travel under the force of the control spring 88 in approximately two minutes, although dimensions of the parts may be selected permitting a shorter or longer period of travel as desired. The control piston 80 will thus move gradually upwardly until the open areas of the V-notches 93 are decreased to a point at which the reduced rate of flow through the metering orifice means 97 produces a pressure differential thereacross which exactly balances the upward force of the control spring 88, at which time upward movement of the control piston 80 will cease. If the rate of flow of operating fluid through the metering orifice means 97 is increased to a rate producing a pressure differential across the metering orifice means 97 twice that required to balance the upward force exerted by the control spring 88, then the control piston 80 will move downwardly at a rate requiring approximately two minutes for full travel thereof.

However, if the rate of flow of operating fluid through the metering orifice means 97 produces a pressure differential thereacross which exceeds the downward force required to balance the upward force exerted by the control spring 88 by more than 20%, then this excess pressure differential, which is also applied to the faces of the valve piston 41, will cause the valve piston 41 to move downwardly, carrying with it the main valve piston 64 toward closed position, which thus restricts the flow of operating fluid therethrough

to this value of 20% in excess of the rate of flow required for maintaining the control piston 80 in equilibrium against the action of the control spring 88. The maximum force, therefore, which can be exerted by the operating fluid to open the control valve means 40 can only be 20% in excess of the force exerted by the control spring 88 when no operating fluid is passing through the metering orifice means 97 and there is no pressure drop thereacross tending to move the control piston 80 toward open position. In order that the rate of opening of the control valve means 40 under their force of 20% of the force of the control spring 88 equal the rate of closing of the control valve means 40 under the full force of the control spring 88, the radial orifice 90 communicates with the control groove 83 at a point 20% of the length of the control groove below the upper end thereof. When the control valve means 40 moves toward open position, operating fluid confined in the control cylinder 81 below the control piston 80 is expelled therefrom through the axial passage 86, past the ball valve element 89, and through the radial orifice 90 into the control groove 83 through which it flows upwardly into the central chamber 42, this expelled operating fluid only passing through 20% of the length of the control groove 83. When the control valve means 40 is moved toward closed position, operating fluid flows from the central chamber 42 downwardly through the control groove 83, closing the ball valve element 89, and thus is forced to flow through the entire length of the control groove 83 to reach the lower end of the control cylinder 81 to permit upward movement of the control piston 80. It will thus be understood that the lower end of the control cylinder 81 below the control piston 80 operates as a dash-pot to provide a gradual timed movement of the control piston 80 in both directions, the axial passage 86, the ball valve element 89, and the radial orifice 90 acting to equalize the rates of movement of the control piston 80 in both directions.

If it is assumed that operating fluid is being supplied to the flow governor 30 at a predetermined constant rate such that the pressure differential across the metering orifice means 97 is such that the control valve means 40 is 25% opened, then, under this condition of operation the main valve means 39 will be entirely opened and there will be no movement of either means. If the rate of flow is then slightly increased, for example by 10%, the control valve means 40 will gradually open until it will permit the passage therethrough of this increased amount of fluid flow without any increase in pressure differential across the metering orifice means 97, and therefore there will be no increase in pressure differential across the valve actuating means 38, and the main valve means 39 will remain in open position. If, however, an attempt is made to increase the rate of flow of operating fluid by 50%, or if the flow tends to increase to such a value for any reason, the pressure differential across the metering orifice means 97 will exert a downward force on the valve actuating means 38 sufficient to move the valve piston 41 downwardly to close or partially close the main valve means 39 against the upward force exerted by the main valve spring 60 to a point where the rate of flow of operating fluid cannot exceed the original setting by more than 20%. This 20% increase in rate of flow of operating fluid, however, will increase the pressure differential across the meter-

6
ing orifice means 91, resulting in a slow downward movement of the control piston 80 against the action of the control spring 88 and the dash-pot effect provided by the control cylinder 81 and associated passages, to open the control orifice member 40 sufficiently to permit the 50% increase in rate of flow of operating fluid therethrough, but a considerable period of time will be required for this due to the throttling action of the control groove 83. It will be appreciated that the desired controlled changes in the rate of flow of operating fluid through the supply tubing 31 are accomplished by adjusting the rate at which the surface pumping mechanism 32 delivers operating fluid to the supply tubing.

It will therefore be apparent that the maximum instantaneous increase in operating speed of the fluid operated pump 26 cannot be greater than 20% in excess of the speed at which it was operating at the time the operating fluid flow conditions changed so as to tend to cause an increase in speed. For example, if the fluid operated pump 26 is receiving solid well fluid from the well on one stroke and all gas on the succeeding stroke, the rate of the stroke on which it receives all gas will not exceed by more than 20% the speed of the preceding stroke on which it was pumping solid well fluid. It is therefore clear that the control valve means 40 will automatically adjust itself either up or down between zero and its maximum capacity so as to limit the instantaneous increase in rate of flow of operating fluid therethrough so that the speed of the fluid operated pump 26 will never momentarily increase more than 20%, whether the fluid operated pump is running at one stroke per minute or one hundred strokes per minute.

In the above examples a flow governor designed for a 20% regulation with the same rate of change in both directions has been described. 40 It will be apparent, however, that by changing the ratios of the springs to the projected areas which they balance, any desired per cent regulation may be obtained without departing from the spirit of the invention. To obtain the same rate of change in both directions, the orifice 90 should communicate with the control groove 83 at a point measured from the top of the groove which is the same per cent of the total length of the groove as the per cent regulation desired. Moreover, different rates of movement of the control piston 80 in both directions can be obtained by changing the point at which the orifice 90 communicates with the control groove 83.

It is also to be noted that the flow governor reaches its maximum capacity when the control valve means 40 is in fully opened position. This top limit of capacity can be adjusted if desired by varying the area of the V-notches 93 or by varying the length of the tubular stem 85 or associated parts to provide a different limiting stop effect for the control piston 80. Such changes will be readily apparent to one skilled in the art, and do not depart from the spirit of my invention.

I claim as my invention:

1. In a device for governing the rate of flow of a high pressure fluid, the combination of: walls forming a metering orifice through which said pressure fluid is adapted to flow so as to impress a pressure differential on said metering orifice, 70 said orifice having a variable effective metering area; throttle valve means through which said pressure fluid is adapted to flow, said throttle valve means being connected in series with said metering orifice; means for applying said pres-

sure differential on said metering orifice to control the throttling action of said throttle valve means; and means for varying the effective metering area of said metering orifice.

2. In a device for governing the rate of flow of a high pressure fluid, the combination of: means forming a metering orifice through which said pressure fluid is adapted to flow so as to impress a pressure differential on said metering orifice; throttle valve means through which said pressure fluid is adapted to flow, said throttle valve means being connected in series with said metering orifice; means for applying said pressure differential on said metering orifice to control the throttling action of said throttle valve means; and means for varying the effective flow capacity of said metering orifice, said means being responsive to changes in the rate of flow and being arranged and constructed so as to prevent the rate of flow from suddenly increasing by more than a predetermined amount above the then prevailing rate of flow, but thereafter automatically permitting a gradual increase in said rate of flow above said predetermined amount.

25 3. In a device for governing the rate of flow of a high pressure fluid, the combination of: valve means for throttling the flow of said high pressure fluid; a cylinder having a piston therein operatively connected to said valve means; means 30 forming a metering orifice through which said high pressure fluid passes so as to impress a pressure differential on said metering orifice, said metering orifice being connected in series with said valve means; means for applying the pressure differential on said orifice to the faces of said piston so as to control the action of said valve means; control means for controlling the pressure differential applied to said piston, said control means including means for restricting the rate of operation of said control means and being responsive to changes in the rate of flow and being arranged and constructed so as to prevent the rate of flow from suddenly increasing by more than the predetermined amount above the then prevailing rate of flow, but thereafter automatically permitting a gradual increase in said rate of flow above said predetermined amount.

4. In a device for governing the rate of flow of a high pressure fluid, the combination of: valve means for throttling the flow of said high pressure fluid through said valve means; a cylinder having a piston therein operatively connected to said valve means; walls forming a metering orifice through which said high pressure fluid passes so as to impress a pressure differential on said metering orifice, said metering orifice being connected in series with said valve means; means for applying the pressure differential on said orifice to the faces of said piston so as to control the action of said valve means; and control means for controlling the pressure differential applied to said piston, said control means including a control piston adapted to vary the normally effective flow capacity of said metering orifice and a dash-pot for restricting the rate of movement of said control piston, said control means operating in response to a change in the rate of flow of said pressure fluid.

5. In a device for governing the rate of flow of a high pressure fluid, the combination of: valve means for throttling the flow of said high pressure fluid through said valve means; a cylinder having a piston therein operatively connected to said valve means; walls forming a metering orifice through which said high pressure fluid

passes so as to impress a pressure differential on said metering orifice, said metering orifice being connected in series with said valve means; means for applying the pressure differential on said orifice to the faces of said piston so as to control the action of said valve means; and control means for controlling the pressure differential applied to said piston, said control means including a control piston adapted to vary the normally effective flow capacity of said metering orifice, means for applying the force exerted by said pressure differential on said metering orifice to said control piston tending to move said control piston in one direction, and means for exerting a force on said control piston tending to move said control piston in a direction opposite to said first direction, said control means operating in response to a change in the rate of flow of said pressure fluid.

6. In a device for governing the rate of flow of a high pressure fluid, the combination of: valve means for throttling the flow of said high pressure fluid through said valve means; a cylinder having a piston therein operatively connected to said valve means; walls forming a metering orifice through which said high pressure fluid passes so as to impress a pressure differential on said metering orifice, said metering orifice being connected in series with said valve means; means for applying the pressure differential on said orifice to the faces of said piston so as to control the action of said valve means; and control means for controlling the pressure differential applied to said piston, said control means including a control piston adapted to vary the normally effective flow capacity of said metering orifice, means for applying the force exerted by said pressure differential on said metering orifice to said control piston tending to move said control piston in one direction, means for exerting a force on said control piston tending to move said control piston in a direction opposite to said first direction, and means for restricting the rate of movement of said control piston when said forces thereon become unbalanced, said control means operating in response to a change in the rate of flow of said pressure fluid.

7. In a device for governing the rate of flow of a high pressure fluid, the combination of: valve means for throttling the flow of said high pressure fluid through said valve means; a cylinder having a piston therein operatively connected to said valve means; walls forming a metering orifice through which said high pressure fluid passes so as to impress a pressure differential on said metering orifice said metering orifice being connected in series with said valve means; means for applying the pressure differential on said orifice to the faces of said piston so as to control the action of said valve means; and control means for controlling the pressure differential applied to said piston, said control means including a control piston in a control cylinder, the lower end of the cylinder forming a dash-pot for restricting the rate of movement of said control piston, walls forming a restricted passage between the ends of said control piston, and means for varying the effective length of said passage.

8. In a device for governing the rate of flow of a high pressure fluid, the combination of: walls forming a variable maximum capacity metering orifice through which said high pressure fluid passes to create a pressure differential on said orifice, said orifice having a variable effective metering area; and control means for con-

trolling the effective metering area of said orifice, said control means including walls forming a cylinder having a control piston therein tending to move in one direction in response to force applied to said control piston by said pressure differential, means for exerting a force tending to move said control piston in a direction opposite to said first direction, and means for restricting the rate of movement of said control piston when said forces thereon become unbalanced.

9. In a device for governing the rate of flow of a high pressure fluid, the combination of: walls forming a variable area metering orifice through which said high pressure fluid passes to create a pressure differential on said orifice; control means movable between open and closed positions in said orifice for controlling the effective area of said orifice in response to a change in the rate of flow of said pressure fluid; and means for equalizing the rates of movement of said control means both toward and away from said open position.

10. In a device for governing the rate of flow of a high pressure fluid, the combination of: walls forming a metering orifice through which said pressure fluid is adapted to flow so as to impress a pressure differential on said metering orifice; throttle valve means through which said pressure fluid is adapted to flow, including a valve chamber, a plurality of valve ports leading into said chamber, and valve closure means for closing said valve ports, said valve ports being disposed so as to equalize the fluid pressures on said closure means, said throttle valve means being connected in series with said metering orifice; and means for applying said pressure differential on said metering orifice to control the throttling action of said throttle valve means.

11. In a fluid operated pumping system for wells, the combination of: a fluid operated pump disposed in a well and adapted to pump well fluid therefrom; tubing means extending downwardly through said well for conveying an operating fluid under high pressure to operate said pump; means in the line of said tubing means, including a valve and control means provided with a variable area metering orifice connected to said valve, so constructed and arranged as to permit an increase in the flow of said operating fluid to said pump at a predetermined controlled rate but preventing sudden substantial increases in said rate of flow, so as to prevent racing of said pump upon a sudden decrease in the pumping load thereon but permitting substantial increases in the production capacity of said pump during pumping thereof in response to a gradual increase in said rate of flow; and means on the surface of the ground for supplying said operating fluid to said pump through said tubing.

12. In a device for governing the rate of flow of a pressure fluid, the combination of: means forming a metering orifice through which pressure fluid passes to create a pressure differential on said orifice, said orifice having a variable effective metering area; movable control means connected with an element of said orifice forming means, said control means being movable for varying the effective area of said orifice in response to a change in the rate of flow of said pressure fluid, said control means being responsive to sudden changes in the rate of flow but being arranged and constructed so that the flow can be increased suddenly only by a predetermined amount above the then established rate of flow but immediately thereafter can be gradually

increased to rates above said predetermined amount; and means for restricting the rate of movement of said control means.

13. In a fluid operated pumping system for wells, the combination of: a fluid operated pump disposed in a well and adapted to pump well fluid therefrom; tubing means extending downwardly through said well and connected to said pump; means for supplying operating fluid under pressure through said tubing to said pump; and means in said well and in said line of tubing, including a valve and control means provided with a variable area metering orifice connected to said valve, so constructed and arranged as to prevent the rate of flow of said operating fluid through said tubing from suddenly increasing by more than a predetermined amount above the then established rate of flow but immediately thereafter automatically permitting a gradual controlled increase in said rate of flow above said predetermined amount, whereby the production capacity of said pump can be substantially increased during operation thereof and said pump at all times is prevented from racing at excessive speed upon a sudden reduction in pumping load thereon.

14. In a device for governing the rate of flow of fluid under pressure, the combination of: valve means adapted to control a flow of fluid under pressure therethrough; and valve control means in series with said valve means and connected thereto, said valve control means including a variable area metering orifice and being so constructed and arranged that it controls said valve means so as to prevent the rate of flow of

5 said fluid from suddenly increasing by more than a predetermined amount above the then established rate of flow, but immediately thereafter automatically permits a gradual increase in the rate of flow above said predetermined amount.

10 15. In a device for governing the rate of flow of fluid under pressure, the combination of: valve means adapted to control a flow of fluid under pressure therethrough; control means for said valve means including a variable-area metering orifice in series with said valve means, the effective area of said metering orifice being variable in response to fluctuations in the rate of flow of fluid therethrough; and means for preventing the fluid pressure drop across said metering orifice from momentarily exceeding a predetermined maximum.

15 20 25 30 35 16. In a device for governing the rate of flow of fluid under pressure, the combination of: valve means adapted to control a flow of fluid under pressure therethrough; piston means operatively connected to said valve means; and control means operatively connected to said valve means and including a variable area metering orifice in series with said valve means and adapted to impress the pressure differential thereon on said piston to tend to cause said piston to actuate said valve means, the effective area of said metering orifice increasing gradually in response to an increase in the rate of flow of said fluid therethrough, but said control means being so constructed and arranged as to prevent a sudden increase in the effective area of said metering orifice.

CLARENCE J. COBERLY.
